TOBACCO PIPE CONSTRUCTION

Albert L. Vogel, Minneapolis, Minn.

Application November 18, 1933, Serial No. 698,649

11 Claims. (Cl. 131—12)

This invention relates to a tobacco pipe, such as ordinarily used for smoking tobacco.

It is an object of this invention to provide a structure of pipe which in use will have a very effective draft and which is arranged so that the tobacco will be uniformly burned in all parts of the tobacco receiving chamber.

It is a further object of the invention to provide a pipe which can be very easily cleaned and which is also so constructed that there will be very little residue left in the pipe after it has been used.

It is another object of the invention to provide a pipe structure comprising a bowl having a stem projecting therefrom and having a tobacco receiving chamber therein, said bowl having a small annular groove thereabout substantially at the bottom of said chamber, a tubular member disposed in said stem extending to said groove and having a portion projecting into said bowl above the bottom thereof from said groove and forming a shield whereby said groove in effect extends under said portion.

It is still another object of the invention to provide a tobacco pipe comprising a bowl having a stem projecting therefrom and having a tobacco receiving chamber therein, a mouthpiece arranged to form a continuation of said stem and having a small draft passage therethrough, a tubular member preferably of metal having one end permanently secured in said mouthpiece and insertable into said stem, the same extending through said stem to said chamber and having a part extending into said chamber spaced from the bottom thereof and forming a shield.

These and other objects and advantages of the invention will be fully set forth in the following description made in connection with the accompanying drawing, in which like reference characters refer to similar parts throughout the several views and in which:

Fig. 1 is a central vertical section through the pipe;

Fig. 2 is a top plan view of the pipe shown in Fig. 1;

Fig. 3 is a transverse vertical section taken on line 3—3 of Fig. 1 as indicated by the arrows;

Fig. 4 is a perspective view of a part used; and

Figs. 5 and 6 are perspective views of modifications of the part shown in Fig. 4.

Referring to the drawing, a pipe is shown comprising a bowl 10 having a stem portion 10a projecting therefrom and secured thereto, said stem 55 being shown as integral with said bowl. Bowl

10 has a chamber 10b therein adapted to receive the tobacco and while this chamber may be variously formed, in the embodiment of the invention illustrated, it is shown as substantially cylindrical. Said bowl 10 has at the bottom of 5 chamber 10b an annular groove 10c extending thereabout, the same being shown as of substantially semi-circular form in cross section. A comparatively large bore or passage 10d extends outward from chamber 10b and groove 10c substantially centrally of stem 10a. At some distance from chamber 10b the passage or bore in stem 10a is enlarged as shown at 10g thus providing a shoulder 10e. The chamber 10b is shown as having a small semi-spherical depression 10f centrally of its bottom. When passage 10d is bored the drill continues the bottom of bore 10d inwardly to depression 10f. A mouthpiece 11 is provided, the same forming a continuation of stem 10a and having its sides flush with the sides 10 of stem 10a. Mouthpiece 11 has a comparatively small draft passage 11a extending centrally therethrough. Said mouthpiece is bored and threaded at its inner end to receive a threaded end 12a of a tubular member 12 preferably made of metal, such as aluminum or steel. Member 12 has a comparatively small draft passage 12b therethrough aligned with and forming a continuation of draft passage 11a. Member 12 has spaced collars 12c and 12d thereon of larger diameter 20 than the other portions of said member. Inner collar 12d abuts against shoulder 10e and member 12 has a portion 12e extending inwardly from collar 12d, which portion is threaded into passage 10d. Portion 12e terminates substantially at the 25 outer edge of groove 10c and has a portion 12f projecting into the chamber 10b, said portion 12f extending from the top of portion 12e and the same has its inner end curved downwardly. It will be noted that the sides of portion 12f are 30 horizontally aligned substantially with the axis of passage 12b. It will also be noted that since portion 12e terminates at the outer edge of groove 10c, said groove in effect extends under the portion 12f. It will also be noted that there is an 35 annular chamber in stem 10a about the member 12 between collars 12c and 12d.

In operation, when the mouthpiece 11 is to be removed from bowl 10 and stem 10a, the same will be rotated and member 12 will unscrew from the bowl 10 at the portion 12e. After portion 12e leaves the bore or passage 10d, member 12 can be withdrawn rectilinearly from the stem. The parts can be reassembled by again inserting member 12 in the stem and screwing portion 12e 55

into passage 10d until collar 12d abuts shoulder 10e. Shoulder 10e is provided to form a stop engaged by collar 12d to determine the longitudinal position of member 12. With the pipe 5 assembled, tobacco is placed as usual in chamber 10b and lighted. The air will be drawn downwardly through the tobacco and through the draft passages 12b and 11a. The groove 10c affords a passage for air completely around the 10 chamber 10b at its bottom and this air can readily pass beneath portion 12f and into the end of passage 12b. The portion 12f forms a shield preventing pieces of tobacco from being drawn into the draft passage 12b. At the same time 15 air can pass in groove 10c beneath member 12f and into passage 12b. The groove thus cooperates with the shield 12f in affording a passage of air into the draft passage 12b. The air being drawn into groove 10c causes a uniform downward draft around the wall of chamber 10b and causes a desirable and uniform burning of the tobacco. Any liquid collecting in the bottom of chamber 10b can not pass out except through 20 draft passage 12b since the threaded portion 12e prevents the passage of any liquid therewith. When mouthpiece 11 and member 12 are withdrawn as above described, the draft passages can be easily and quickly cleaned. It has been found in practice that very little liquid collects in the 25 bottom of the chamber 10b. The temperature at this point as is well known, is quite high and the metal in member 12, particularly portions 12e and 12f, have the effect of evaporating any liquid. When mouthpiece 11 and member 12 are 30 removed, portion 12f can be used as a scraper to scrape any carbon or ashes which have been deposited on the walls of chamber 10b. The annular chamber around member 12 between collars 12c and 12d tends to keep the stem 10a cool. 35 It will also be noted that the outer side of collar 12c is flush with the outer end of stem 10a and a tight fit is thus had between the outer end of the stem and the inner end of mouthpiece 11.

In Fig. 5 a modified form of the invention is 40 shown. A member 14 quite similar to member 12 is shown and the same has collars 14c and 14d thereon. Member 14 has a threaded portion 14a similar to portion 12a which is threaded into the mouthpiece 16. Said mouthpiece has the draft 45 opening 16a therethrough which is alined with the draft opening through member 14. Mouthpiece 16 has a reduced terminal portion 16b forming an annular shoulder 16c. This reduced portion 16b is of the same diameter as collar 14c and said reduced portion and collar fit into the 50 end of stem 10a with a tight fit. These parts form the tenon which holds the stem and mouthpiece together. Member 14 has the portion 14e corresponding to the portion 12e of member 12, 55 but the same has a smooth periphery and when member 14 is used passage 10d will have a smooth wall and portion 14e will fit snugly therein. Member 14 also has the portion 14f similar to portion 12f but shown as somewhat longer. Portion 14f will extend past the center of the bowl chamber 10b and its terminal end will substantially contact with the bottom of chamber 10b. It will be seen that when member 14 is used the 60 mouthpiece 16 in member 14 can be drawn rectilinearly from the stem 10a. There are no threads to unscrew and as stated the parts are held together by the frictional engagement of portion 16b and collar 14c in the stem 10a as well as by the friction of portion 14e in passage 65 10d.

In Fig. 6 a member 15 is shown which may be used in place of member 12. Member 15 has the portion 15a which will be threaded into the mouthpiece 11 as is the portion 12a. Member 15 has the spaced collars 15c and 15d. Collar 15c will fit into the end of the stem as does collar 12c but is much longer so that it will have additional friction to hold the mouthpiece and stem together. Portion 15e like portion 14e has a smooth periphery and will fit into the smooth passage 10d. Portion 15f is similar to portion 12f. When member 15 is used it will be seen that mouthpiece 11 and said member may be drawn rectilinearly from stem 10a, the parts as stated being held together by the friction of portions 15c and 15e in their respective passages in stem 10a.

From the above description it is seen that applicant has provided a very simple and efficient structure of pipe. The tobacco is evenly burned as above explained due to the downward draft along the wall of chamber 10b, the air passing into groove 10c and then into the member 12. Any air which passes down through the tobacco can also pass under member 12f and into 20 passage 12b. The moisture which collects in the bottom of pipes is caused chiefly by condensation of moisture in the atmosphere or in the tobacco. The moisture carried in the heated air near the bottom of the tobacco receiving chamber ordinarily passes into the stem and is cooled so that moisture is precipitated. With the present structure the heat from the bottom of the bowl is absorbed by member 12 and portions 12f and 12e thereof. Member 12 is thus heated and 25 when the moisture laden air passes therewith condensation does not occur. Very little moisture therefore collects in the pipe of this invention. The threaded portion 12e prevents any moisture which might form from passing back 30 into passage 10g. The parts are easily disassembled and the draft passage can be very readily and easily cleaned by passing any sort of swab or cleaner through the passages 12b and 11a. The parts of the device are few and easily made 35 and assembled. The pipe has been amply demonstrated in actual practice, found to be unusually efficient and satisfactory to the smoker and has been enthusiastically received by quite a few smokers.

It will, of course, be understood that various changes may be made in the form, details, arrangement and proportions of the parts, without departing from the scope of applicant's invention, which generally stated, consists in a 50 device capable of carrying out the objects above set forth in the parts and combinations of parts disclosed and defined in the appended claims.

What is claimed is:—

1. A pipe structure having in combination, a 55 bowl with a stem attached thereto, a mouthpiece arranged to aline with and form a continuation of said stem and having a small draft passage therethrough, a chamber in said bowl for receiving tobacco, said bowl having an annular groove thereabout substantially at the bottom of said chamber and having a comparatively large passage extending from said chamber and groove into said stem, a tubular member secured in said mouthpiece having a small draft passage 60 therethrough alining with and forming a continuation of the draft passage in said mouthpiece, said member extending through said stem and having a portion fitting in said first mentioned passage, said portion having a shield-forming 65

part extending from its upper side into said bowl over the bottom thereof, the bottom of said part except at the terminal portion also being above said groove whereby said groove extends under 5 said part and air can pass around said groove beneath said part and into said last mentioned passage.

2. A pipe structure having in combination, a bowl with a stem attached thereto, a mouthpiece 10 arranged to form a continuation of said stem and having a comparatively small draft passage therethrough, a chamber in said bowl for receiving tobacco, a comparatively large passage extending from said chamber into said stem and 15 a larger passage extending outward in said stem some distance from said chamber forming a shoulder with said last mentioned passage and a tubular member secured in said mouthpiece insertable in said stem, the same having a comparatively 20 small draft passage therethrough alining with said draft passage in said mouthpiece, said member having a shoulder thereon fitting against said shoulder to form a stop and having a portion fitting in said first mentioned passage and 25 extending inwardly from said shoulder to said chamber and having a portion projecting into said bowl and spaced from the bottom thereof.

3. A pipe structure having in combination, a bowl with a stem attached thereto, a mouthpiece 30 arranged to form a continuation of said stem and having a comparatively small draft passage therethrough, a chamber in said bowl for receiving tobacco, a comparatively large passage extending from said chamber into said stem and 35 a tubular member secured in said mouthpiece having a comparatively small draft passage therethrough alined with and forming a continuation of said draft passage in said mouthpiece, said member being insertable in said stem and 40 having a portion extending through and fitting in the outer portion of said last mentioned passage and having a portion threaded into and extending through the inner portion of said last mentioned passage, said member having a stop 45 means thereon engaging said stem to limit its inward movement and having a portion projecting into said bowl above the bottom thereof forming a shield.

4. A pipe structure having in combination, a 50 bowl with a stem attached thereto, a mouthpiece arranged to form an extension of said stem and having a comparatively small draft passage therethrough, said bowl having a chamber there- 55 in for receiving tobacco, a comparatively large passage extending from said bowl into said stem and a tubular metal member having a threaded terminal portion screwed into and carried by said mouthpiece, said member having a comparatively small draft passage extending therethrough 60 alined with and forming an extension of said draft passage in said mouthpiece, said stem having a larger passage therethrough adjacent its outer edge forming a shoulder, spaced collars on said member, one of which fits against said 65 shoulder to form a stop and the other of which is disposed at the outer end of said stem, said member having a threaded portion extending inwardly from said shoulder fitting in said second mentioned passage, the same acting to prevent 70 the passage of any liquid outwardly to said larger passage and a portion projecting from the upper side thereof into said bowl and spaced from the bottom of said bowl.

5. A pipe structure having in combination, a 75 bowl with a stem attached thereto, a mouthpiece

arranged to form a continuation of said stem and having a comparatively small draft passage therethrough, a chamber in said bowl for receiving tobacco, a comparatively large passage extending from said chamber into said stem and a tubular member secured in said mouthpiece having a comparatively small draft passage therethrough alined with and forming a continuation of said draft passage in said mouthpiece, said member being insertable in said stem 10 and having a portion extending through and fitting said second mentioned passage, stop means on said member engaging said stem to limit the inward movement thereof, said member having a portion projecting into said bowl forming a shield and adapted to conduct heat to said member. 15

6. A pipe structure having in combination, a bowl with a stem attached thereto, a mouthpiece 20 arranged to aline with and form a continuation of said stem and having a small draft passage therethrough, a chamber in said bowl for receiving tobacco, said bowl having an annular groove thereabout substantially at the bottom of said chamber and having a passage extending therefrom into said stem, a member extending through said stem having a small draft passage therethrough and having a portion closely fitting into said last mentioned passage but terminating at said groove, and having a second portion 25 extending above said groove into said bowl and shielding the opening into the passage therein, whereby air may be drawn down around the entire circumference of said chamber and pass around said groove into the passage in said 30 chamber.

7. A pipe structure having in combination, a bowl with a stem attached thereto, a mouthpiece 35 arranged to form a continuation of said stem and having a comparatively small draft passage therethrough, a chamber in said bowl for receiving tobacco, a comparatively large passage extending from said chamber into said stem and a larger passage extending outward in said 40 stem some distance from said chamber, a member having a bore therethrough alined with the opening in said mouthpiece disposed in said larger passage and having means engaging a portion of said stem for determining its longitudinal position in said stem, said member having a portion 45 threaded into said second mentioned passage, said bowl having an annular groove in the wall of said chamber, the same alining with the bore in said member, said member having a portion thereof terminating at said groove whereby 50 air may be drawn down around the entire wall of said chamber and pass around said groove and into said bore.

8. The structure set forth in claim 7, said member having another portion extending from 55 said portion inwardly into said chamber above said bore, above said groove and above the bottom of said chamber, the same acting as a guard for the end of said bore.

9. A pipe structure having in combination, a 60 bowl with a stem attached thereto, a mouthpiece arranged to form a continuation of said stem and having a comparatively small draft passage therethrough, a chamber in said bowl for receiving tobacco, a comparatively large passage extending from said chamber into said stem and a tubular member secured in said mouthpiece 65 having a comparatively small draft passage therethrough alined with and forming a continuation of said draft passage in said mouthpiece, said 70

member being insertable in said stem and having a portion extending through and fitting said first mentioned passage, said portion and passage therethrough terminating substantially at the 5 wall of said chamber, said member having another portion extending from the top part of said portion and projecting into said chamber and terminating substantially at the center thereof.

10. The structure set forth in claim 9, said 10 last mentioned portion having its terminal end bent downwardly toward the bottom of said chamber.

11. A pipe structure having in combination, a 15 bowl with a stem attached thereto, a mouthpiece arranged to form a continuation of said stem and having a comparatively small draft passage therethrough, a chamber in said bowl for re-

ceiving tobacco, a passage extending from said chamber into said stem, a member having a bore therethrough alined with the opening in said mouthpiece disposed in said stem and having means engaging a portion of said stem for determining its longitudinal position in said stem, said member having a portion disposed in said second mentioned passage, said bowl having an annular groove in the wall of said chamber adjacent the bottom thereof, the same alining with 10 the bore in said member, said member having a portion thereof terminating at said groove whereby air may be drawn down around the entire wall of said chamber and pass around said groove and into said bore. 15

ALBERT L. VOGEL.
